SIDE SLIPPING WEFT DETECTOR

Clifford Darwin, Paxton, Mass., assignor to
Crompton & Knowles Loom Works, Worcester,
Mass., a corporation of Massachusetts

Application June 27, 1951, Serial No. 233,759

11 Claims. (Cl. 139—283)

1 This invention relates to side slipping weft detectors for looms and it is the general object of the invention to provide a weft detector having a feeler finger unit movable in one direction along a depleted bobbin to indicate weft exhaustion but movable also in the opposite direction to avoid weft abrasion without giving an indication of weft exhaustion.

In multishuttle looms employing shifting shuttle boxes it is customary to use a gang of two or more shuttle boxes each capable of holding a shuttle and each movable to active picking position. It is customary in such looms to utilize a shuttle picker which has a hole to receive one tip of the shuttle aligned with it. When the shuttle box is shifted the tip is cammed out of the hole in the picker and the shuttle moves in a direction toward the center of the loom. Furthermore, it is customary to equip the lay with shuttle placer means in the form of inclined plates which act as cams to move an improperly placed shuttle toward the center of the loom during a shift of the shuttle boxes.

When a side slipping weft detector is used at the shifting shuttle box end of a loom it is ordinarily mounted so that when swinging to indicate weft exhaustion it will move away from a stop in a direction opposite to that in which the shuttle is moved by the picker and the aforesaid placer plates as the boxes shift. Because of the stop, however, the detector is not free to move with the shuttle when the latter is moved as described incident to box shift and there is resultant abrasion of the weft. This condition exists more particularly in those looms in which a gang of weft detectors is mounted in front of the shuttle boxes and rises and falls with the latter so that each detector is always in register with its own shuttle box.

It is an important object of the present invention to provide a side slipping weft detector with a feeler finger unit capable of swinging bodily in one direction, such as toward the adjacent end of the lay, to indicate weft exhaustion but mounted so that it can move pivotally in the opposite direction, as toward the far end of the lay, in a reverse direction, without giving indication of weft exhaustion when moving with a shuttle which is being moved along the lay toward the far end of the latter. The motion of the feeler unit in the opposite direction will eliminate abrasion of the weft by the unit and will avoid a false indication of exhaustion.

When a gang of side slipping weft detectors is used to determine the condition of weft in

any one of several shuttles in a gang of shifting shuttle boxes it is necessary to utilize the swinging motion of the indicating detector to effect some control of the loom. In the present instance the control is exercised electrically to stop the loom and each detector is associated with a contact normally held in non-contacting position by its detector but permitted to move to contacting position when the indicating lever therefor swings to indicate weft exhaustion. The description to follow sets forth this type of electric indication, but it is to be understood that certain features of the invention are not limited to this particular way of indicating weft exhaustion for the purpose of controlling loom operation.

In order that the invention may be clearly understood reference is made to the accompanying drawings which illustrate by way of example two embodiments of the invention and in which:

Fig. 1 is a plan view of a lay having shifting shuttle boxes thereon and weft detecting mechanism made according to the preferred form of the invention,

Fig. 2 is a vertical section on line 2—2, Fig. 1, Fig. 3 is an enlarged plan view looking in the direction of arrow 3, Fig. 2, showing the top weft detector for the gang of detectors,

Figs. 4 and 5 are enlarged vertical sections on lines 4—4 and 5—5, respectively, Fig. 3,

Fig. 6 is a horizontal section on line 6—6, Fig. 5,

Fig. 7 is a diagrammatic view illustrating the manner in which the preferred form of the invention operates to cause rocking of the indicating lever in a direction to indicate weft exhaustion when the feeler finger unit indicates depletion of weft,

Fig. 8 is a diagrammatic view illustrating the manner in which the feeler finger unit can have a reverse or opposite motion from that indicated in Fig. 7 when the shuttle is moved toward the center of the loom,

Fig. 9 is an enlarged vertical section on line 9—9, Fig. 1, showing the relation between the shuttle, its picker, and the shuttle placing cams,

Fig. 10 is a diagrammatic view looking generally in the direction of arrow 10, Fig. 1, showing the relation between the gang of shifting shuttle boxes and the gang of weft detectors,

Fig. 11 is a plan view showing the modified form of the invention and indicating the manner in which it operates when indicating weft exhaustion,

Fig. 12 is a view similar to Fig. 11 but indi-

cating the manner in which the detector operates when detecting an ample supply of weft,

Fig. 13 is a view similar to Fig. 11 indicating diagrammatically how the feeler finger unit moves without causing angular motion of the indicating lever when in contact with a weft supply which is being moved incident to camming of the associated shuttle toward the center of the loom, and

Fig. 14 is a vertical section on line 14—14, Fig. 12.

In looms of the type to which the present invention more particularly relates there is ordinarily a gang of shifting shuttle boxes at each end of the lay and upon depletion of weft in any shuttle the loom is stopped to permit hand replenishment of the empty shuttle. Only sufficient parts of the loom are shown to illustrate the invention and the weft detector mechanism has been illustrated as associated with a gang of shifting shuttle boxes at the right hand end of the loom.

Referring more particularly to Figs. 1, 2 and 10, the loom has a stationary breast beam 1 and is provided with a lay 2 which is reciprocated backwardly and forwardly in well-known manner. The lay has a shuttle race 3 along which the picked shuttle travels toward the left as viewed in Fig. 1. A gang G of shuttle boxes has four vertically aligned shuttle box cells 4, 5, 6 and 7 all connected together and mounted on a box lifter rod 8 the vertical position of which is determined by well-known mechanism not shown herein so that any one of the cells 4—7 can be in active position with its shuttle actively placed for picking and aligned with the shuttle race 3.

The lay is provided with a picker rod 10 to guide a picker 11 which will be moved from the right to the left as viewed in Fig. 1 by a picker stick 12 during a picking operation of the loom. The lay has inner and outer guides 13 and 14 respectively stationary with respect thereto to guide the gang G as it rises and falls. Each shuttle box has a shuttle binder designated generally at 15 having a slot 16 therein for the feeler finger unit or element of a weft detector mechanism.

The loom may operate with more than four shuttles, but in the present instance only four are shown at S1, S2, S3 and S4. Each shuttle will have at the right end thereof as viewed in Fig. 1 a tip 17 which will enter a hole 18 in the picker 11 when the shuttle enters the associated box from the left. Secured to the lay is shuttle placing means including upper and lower inclined or cam plates 19 and 20, see Fig. 9.

When a shuttle enters a shuttle cell in active position its advancing tip end will enter the hole 18 between the upper and lower cam plates 19 and 20, see Fig. 9. If the shuttle is then to be inactive on the next beat of the loom the box lifter rod 8 will move vertically one way or the other to shift the gang G and the tip 17 will be cammed out of the hole 18 and will also be engaged by one or the other of the inclined cams 19 or 20 to move the shuttle to the left, Fig. 9. Each of the cam plates 19 and 20 leads to a vertical wall 22 which limits motion of a shuttle in engagement therewith in a right hand direction as viewed in Fig. 9. If a shuttle is to remain active for two successive picks there will be no shifting of the gang G and it will be picked out of its cell at the next working stroke of the

picker 11, but ordinarily in pick and pick looms there will be a shift of the shuttle boxes upon arrival of a shuttle therein. Camming of the shuttle toward the center of the loom will start at the beginning of a box shift as the tip 17 leaves the picker hole 18 and is likely to be continued by one or the other of the cams 19 or 20 when the lay reaches its extreme forward or front center position to the right of the position shown in Fig. 10.

A stand 25 secured to the breast beam 1 supports front and back guides 26 and 27 between which extends a vertically moving weft detector carrier 28. The carrier is connected as at 29 to a rod 30 the lower end of which is operatively connected as at 31 to the box lifter rod 8, Fig. 10. The rod 30 and the carrier rise and fall with the rising and falling of the gang G.

In the preferred form of the invention the carrier 28 has mounted thereon four detector mechanisms designated generally at D1, D2, D3 and D4 for the shuttle box cells 4, 5, 6 and 7, respectively. These detectors D1—D4 are alike and a description will be given of one of them, 25 namely, detector D1.

Detector D1 has a base 35 secured at 36 to the carrier 28. Mounted for horizontal back and forth motion on the base is a slide member 37 which is urged to the rearward direction, to the left as viewed in Figs. 2 and 3, by a compression spring 38 operatively interposed between a front part 39 of the base and a rear part 40 of the slide member 37. A stop screw 41 on the slide member 37 engages a stop 42 on the base to limit rearward motion of the slide member 37 under action of the spring 38 and permits adjustment of the detector in a back and forth direction.

Slide member 37 is formed with a rearwardly extending arm 45 to which is secured an upwardly extending stud 46 held to the arm by a nut 47. Stud 46 comprises a primary pivot on which is mounted an indicating lever element 48 provided with a forwardly extending finger 49 which engages a primary adjustable stop screw 50 in arm 45. A primary torsion spring 51 having one end 52 connected to the indicating lever 48 and having the other end 53 extending through a slot 54 in a shell 55 tends normally to turn the indicating lever element in a counter-clockwise direction as viewed in Fig. 3 to hold the finger 49 against primary stop screw 50. The shell is held in angularly adjusted position on the stud by a set screw 56 and can be moved around the stud 46 to vary the force exerted by the spring 51.

The feeler finger unit, designated at U1, is shown in the preferred form of the invention as comprising an arm 61 mounted to swing on a secondary pivot stud 62 extending upwardly from and secured to the rear part of the indicating lever 48. This arm has a secondary stop 63, see Fig. 6, which engages a stop surface 64 on the indicating lever 48. A secondary torsion spring 65 has one end 66 thereof connected to the arm 61 and has the other end 67 thereof held in a slot 68 of a shell 69 similar to shell 55. Shell 69 is held in adjusted angular position on stud 62 by a set screw 70. The spring 65 acts in a direction opposite to the direction in which spring 51 acts and tends to turn the arm 61 in a clockwise direction with respect to indicating lever 48 as viewed in Fig. 6, thus holding the secondary stops 63 and 75 64 against each other, but permitting separation

of these stops to enable arm 61 to swing in a counter-clockwise direction as viewed in Fig. 6.

A weft feeler 75 is held in longitudinally adjusted position on the arm 61 by a clip 76 and includes a rod 77 to the rear end of which is secured a feeler tip 78 for engagement of weft. The feeler 75 includes also a sleeve or tube 79 in which the rod 77 can slide, and a compression spring 80 tending normally to hold the rod 77 in rearward position, to the left as viewed in Fig. 3, but permitting the rod and feeler tip to move forwardly with respect to arm 61.

Slidably mounted on the sliding member 37 is a contact controlling rod 83 movable in a back and forth direction in front and back bearings 84 and 85, respectively, on the member 37. A contactor 86 is secured by set screw 87 to rod 83 and a compression spring 88 between bearing 84 and the contactor normally urges the contactor and rod rearwardly. The rod is surrounded by a sleeve 90 somewhat shorter than the distance normally existing between the contactor 86 and the rear bearing 85, and the rear end 91 of the rod is ordinarily held against the finger 49 by spring 88. The indicating lever element 48 therefore when in normal position as shown in Fig. 3 acts by reason of the finger 49 to keep the rod 83 and the contactor 86 in normal forward non-contacting position with respect to a contact 93 on a lever 95, see Fig. 1. The latter lever is pivoted as at 96 to the stand 25 and has a stop screw 97 to limit counter-clockwise motion of the lever 95 around its pivot by a spring 98. There is only one of the contacts 93 and it is so located as to register with the contactor 86 of the detector associated with the shuttle in active picking position.

In operation, all of the feeler tips 78 will engage their respective bobbins as the lay moves forwardly toward its front center position. If all the shuttles are provided with ample supplies of weft the feeler tips with respect to their arms 61 will move forwardly while embedded in weft and will not cause angular motion of their indicating levers, and rods 83 will remain unchanged. If any shuttle is depleted of weft, however, its feeler tip will slide from the full line position to the right along the depleted bobbin to the dotted line position, see Fig. 7, toward the adjacent end of the lay, due to the fact that the axis of the feeler rod 77 is offset from the primary pivot of the indicating lever with respect to the length of the bobbin. During slipping of the feeler tip the unit U1 moves bodily toward the near end of the lay, and the secondary stops 63 and 64 cooperate to cause the unit to rock the associated indicating lever 48 in a clockwise direction, Fig. 3, thereby moving its finger 49 away from the primary stop 50 and out of the path of the rear end of the corresponding rod 83 and permitting the latter to be moved rearwardly to indicating position by its spring 88 to move the associated contactor 86 into active or indicating position. If the contactor is registered with contact 93 a circuit (not shown) will be closed to stop the loom.

If a previously active shuttle is shifted out of active position and the feeler tip 78 corresponding to the shuttle is partly embedded in the weft of the shuttle the feeler finger unit will be shifted from the full line position, Fig. 8, toward the opposite end of the lay to the dotted line position as the shuttle is cammed toward the center of the loom without, however, causing movement of the indicator lever 48. When the bobbin B moves to the dotted line position shown in Fig. 8, therefore

its weft W will not be abraded because of the fact that the feeler finger unit U1 is free to swing on the secondary pivot. As soon as the gang G moves rearwardly far enough to disengage the weft from the feeler tip 78 spring 65 will return the feeler finger unit to its normal position and will reestablish engagement of the stops 63 and 64 as shown in full lines in Fig. 8.

In the modified form of the invention, in which much of the matter thus far described will be used, each weft feeler finger unit U2 comprises an arm 100 having a tip 101 for engagement with the weft W1 of a bobbin B1. The arm 100 is mounted to swing on a secondary pivot stud 102 on the rear part of an indicating lever 103 somewhat similar to lever 48. A secondary stop 104 is secured to the lever 103 and a secondary spring 105 tends normally to hold the arm 100 against the stop 104 but permits the arm to move angularly with respect to lever 103 without causing the latter to have an indicating motion.

In the operation of the modified form of the invention each weft feeler finger unit U2 will normally be held against its stop 104 and when its tip 101 engages an ample supply of weft W1 the unit U2, lever 103, and slide 37 will move forwardly on its base 35 during a detecting operation. In this modified form of the invention the spring 38 not only permits back and forth adjustment of the feeler finger unit as described in connection with the preferred form of the invention, but also permits the slide 37 to assume the position shown in Fig. 12 when the lay is on front center and the detector is engaging ample weft. After the detecting operation spring 38 returns the slide 37 and parts mounted on it rearwardly to the left, Fig. 12, in readiness for another detecting operation.

If a feeler unit U2 engages a depleted supply of weft on a bobbin B1 it will slide along the latter from the full line to the dotted line position shown in Fig. 11 and the associated slide 37 will remain stationary. This bodily movement of the unit U2 toward the near end of the lay will cause rocking of the corresponding indicating lever 103 to indicating position and the associated rod 83 will move rearwardly, as already described for the preferred form.

If a feeler unit U2 is in engagement with a shuttle which is being moved away from active position and is being cammed toward the center of the loom, the unit U2 will then move from the full line to the dotted line position shown in Fig. 13 away from its stop 104, but without causing angular motion of lever 103. Under these conditions indication of weft exhaustion will not be given and the slide 37 will move forwardly as suggested in Fig. 12. After movement of the unit U2 to the dotted line position, Fig. 13, the secondary spring 105 will return the unit U2 to the stop 104 as the lay moves rearwardly.

As shown for instance in Fig. 12 it is desirable that a line joining the axes of the primary and secondary pivots 46 and 102 be substantially perpendicular to the axis of the bobbin being detected, the purpose of this relation being to reduce the likelihood that movement of unit U2 from the full line to the dotted line position, Fig. 13, will cause angular indicating motion of the lever 103.

After either the preferred or the modified form of weft feeler or detector has given indication of weft exhaustion the rod 83 corresponding to the depleted shuttle in the actively placed shut-

the box will be in rearward position to prevent the associated indicating lever from returning to its normal position. In order to reset the detector mechanism so that the rod 83 in indicating position can be returned to its normal position the lever 95 will be rocked about its pivot 96 by operation of some part of the loom which moves when the loom is stopped, such as either the shipper or the brake handle when it moves to stopping position.

From the foregoing it will be seen that the invention sets forth simple means by which the feeler finger unit of a side slipping weft detector mechanism is capable of swinging in usual manner to indicate weft exhaustion and is also capable of swinging in the opposite direction without indicating to avoid abrasion of the weft. In the preferred form of the invention the feeler finger unit U1 includes a sliding feeler on an arm movable pivotally about the secondary pivot, whereas in the modified form of the invention the weft feeler finger unit U2 comprises a feeler arm 100 mounted directly on the secondary pivot. In both forms of the invention a primary spring tends to move the indicating lever toward the far end of the lay back to its normal position and a secondary spring acts to move the weft feeler finger unit toward the adjacent end of the lay back to its normal position. In the modified form the slide 37 moves backwardly and forwardly against the action of spring 38, whereas in the preferred form of the invention the slide 37 will be stationary whether or not the detector is indicating weft exhaustion. Because of this last named fact the spring 38 will not be necessary in the preferred form of the invention, but it is shown herein as used with both forms of the invention so that either feeler finger unit U1 or U2 can be used. Also, the indicating lever and the feeler finger unit constitute an assembly for replacement of feeler fingers on weft detector mechanisms now in use.

Having now particularly described and ascertained the nature of the invention and in what manner the same is to be performed, what is claimed is:

1. In side slipping weft detector mechanism for a loom having a bobbin at one end of a lay movable toward the opposite end of the lay during a weft detecting operation, a primary pivot, an indicating lever swingable on the primary pivot to move a part thereof from the normal position thereof toward said one end of the lay to weft exhaustion indicating position, a secondary pivot on said part of the indicating lever spaced from the primary pivot, a feeler finger unit movable angularly on the secondary pivot from the normal position thereof toward said other end of the lay, said unit being slideable along a depleted bobbin toward said one end of the lay, and means on the indicating lever engaging the feeler unit preventing the latter from turning on said secondary pivot relatively to the indicating lever and causing the latter to be turned on the primary pivot to said indicating position by said feeler unit when the feeler unit slides on a depleted bobbin.

2. In side slipping weft detector mechanism for a loom having a bobbin at one end of a lay movable toward the opposite end of the lay during a weft detecting operation, an indicating lever swingable to move a part thereof in a given direction from the normal position thereof to indicating position, a feeler finger unit moved laterally in said given direction when en-

gaged by a depleted bobbin and pivoted on said part of the lever at a point spaced from the axis of the lever, primary stop means limiting movement of the lever in a direction opposite to said given direction, secondary stop means limiting motion of the unit relative to said lever in said given direction causing the unit when moving laterally in said given direction to swing the lever to indicating position, said unit when engaged by the bobbin when the latter moves toward said opposite end of the lay, provided ample weft is on the bobbin, being moved away from the secondary stop means by the bobbin in a direction opposite to said given direction, and said primary stop means preventing angular motion of the indicating lever when the unit moves in said opposite direction.

3. In side slipping weft detector mechanism for a loom having a bobbin at one end of a lay movable toward the opposite end of the lay during a weft detecting operation, a primary pivot, an indicating lever swingable on the primary pivot to move a part thereof toward said one end of the lay to weft exhaustion indicating position, a primary stop limiting motion of said part of the lever toward the opposite end of the lay, a secondary pivot on said part of the lever, a feeler finger unit on said secondary pivot movable about the latter in a direction toward the opposite end of the lay, and secondary stop means limiting motion of the unit relative to the lever in a direction toward said one end of the lay, said unit when engaging a depleted bobbin during a detecting operation being movable toward said one end of the lay and cooperating with said secondary stop to move said lever to indicating position, said unit when in engagement with the bobbin during movement of the latter toward said opposite end of the lay, provided ample weft is present on the bobbin, being swung about said secondary pivot by the bobbin away from said secondary stop.

4. The detector mechanism set forth in claim 3 wherein a primary spring holds the indicating lever against said primary stop and a secondary spring holds said unit against the secondary stop.

5. The detector mechanism set forth in claim 4 wherein said primary spring exerts a turning force on said lever in a direction opposite to the turning force exerted by the secondary spring on the unit.

6. The mechanism set forth in claim 3 wherein said feeler finger unit comprises an arm pivoted on the secondary pivot and having a weft feeler for engagement with the bobbin slideable thereon.

7. The detector mechanism set forth in claim 3 wherein the feeler finger unit comprises a single arm pivoted on said secondary pivot for engagement with the secondary stop and having a weft feeler tip for engagement with the bobbin.

8. The detector mechanism set forth in claim 7 wherein a line joining the primary and secondary pivots is substantially perpendicular to the bobbin.

9. An assembly for a weft detector mechanism having a primary pivot stud, said assembly comprising an indicator lever for mounting on said primary pivot stud, a stop on the lever, a secondary pivot stud on the indicator lever, a feeler finger unit pivoted on the secondary pivot stud, and a spring normally holding the unit against said stop, said unit when moved bodily in one direction while in engagement with said stop causing movement of the lever and said unit being movable angularly about said secondary

pivot stud away from said stop without causing movement of the indicating lever.

10. The assembly set forth in claim 9 wherein said unit comprises an arm on the secondary pivot stud normally engaging the stop and a weft feeler mounted for sliding movement with respect to the arm.

11. The assembly set forth in claim 9 wherein said unit comprises a single arm having a part thereof normally held against said stop and having a feeler tip on the end thereof remote from the secondary pivot. 10
